EDWIN M. S. CHANDLER, OF TAUNTON, MASSACHUSETTS.

PROCESS OF STORING DRYING OILS.

Application filed April 29, 1925. Serial No. 26,666.

This invention relates to the storage of drying oils, such for example, as linseed oil. In plants where oil cloth, linoleums and the like are manufactured and where, consequently, drying oils are used in relatively large quantities, it is necessary to keep a large supply of oil in storage at practically all times. This oil is boiled before it is used, and it is run into storage tanks immediately after boiling and while still hot. Drying oils oxidize very rapidly, particularly when hot, with the result that a scum or skin of oxidized oil forms on the surface of the oil. This scum has a very tough rubbery consistency, it will not again dissolve in the oil, and unless it is carefully strained out it causes much trouble in the subsequent manufacturing operations. While such a scum breaks up readily in the operation of mixing the oil with the other ingredients used in the manufacture of oil cloth, linoleum, and the like, still it does not entirely disintegrate but remains in a granular condition and produces a lumpy surface in the finished product. The formation of such a scum is, therefore, objectionable both because of the labor involved in getting rid of it, and also because the oxidized oil of which the scum is composed is wasted. This is all the more objectionable because the best part of the oil oxidizes most readily and therefore forms the greater part of the scum.

The present invention aims to overcome these objections and it provides a novel process of storing oil.

The nature of the invention will be readily understood from the following description when read in connection with the accompanying drawings, and the novel features will be particularly pointed out in the appended claims.

Referring now to the drawings,

Figure 1 is a perspective view of a storage tank embodying one feature of the present invention; and

Fig. 2 is a transverse cross sectional view of the tank shown in Fig. 1.

I have discovered that if linseed oil or other drying oil is kept in a substantially constant state of agitation while it is being stored, the formation of an oxidized scum or skin on the surface of the oil is prevented.

This result may be accomplished in a number of forms of apparatus. One such

apparatus is illustrated in the drawings and comprises a horizontal tank 2 preferably of cylindrical form and provided near its opposite ends with heavy circumferential rings 3 and 4. The ring 4 is supported on two grooved rolls 5 and 6, respectively, while the ring 3 is similarly supported by another pair of rolls, one of which is shown at 7. These rolls are mounted in suitable bearing brackets which are supported on bed blocks 8 and 9. Both the rolls 6 and 7 are secured fast on a shaft 10 which carries a pulley 12 that may be connected to any convenient source of power, so that when this shaft is driven the tank 2 will be rotated about its horizontal axis. The tank may be provided with the usual filling inlet 13, normally closed by a plug, and it also has a discharge nozzle 14 equipped with a valve. The usual manhole 15 also is provided.

In using this apparatus the tank may be filled with oil to any desired level. So long as the oil remains in it the tank is rotated at a very slow speed, say for example, one revolution per minute. This requires very little power, but the motion so imparted to the tank is sufficient to keep the oil in it in a substantially constant state of agitation. The oil at the surface and which is in contact with the air thus is constantly being changed, and while this may result in a gradual oxidation of the oil, still there is no opportunity for the oxidized particles of oil to cohere and form a scum or skin on the surface of the oil. Such oxidation as occurs is beneficial in ageing the oil.

This invention is of particular utility in storing boiled oil, since a scum of oxidized oil forms much more quickly on boiled oil than on raw oil.

The invention is also of advantage in storing raw drying oils since the constant agitation promotes the ageing action.

Having thus described my invention, what I desire to claim as new is:

1. That improvement in the method of storing drying oil which consists in maintaining it in a substantially constant state of agitation.
2. That improvement in the method of storing drying oil which consists in confining a body of said oil in a container with a portion of said body exposed to the air, and constantly changing the oil composing the surface so exposed.

3. That improvement in the method of storing drying oil which consists in confining a body of said oil in a closed container, and moving the container sufficiently to keep the oil in substantially constant motion.
4. That improvement in the method of storing drying oil which consists in con-
5. That improvement in the method of storing drying oil which consists in confining a body of oil in a closed container, and rotating said container slowly about a horizontal axis.

EDWIN M. S. CHANDLER.
